UNITED STATES PATENT OFFICE

SIMON M. ROWLAND, OF CLOVERPORT, KENTUCKY

VIOLIN

Application filed April 19, 1928. Serial No. 271,337.

This invention relates to stringed musical instruments of which the violin is typical and aims to increase the volume and insure a consonance of vibration between the strings 5 and the front and back of the instrument.

The invention contemplates a resilient tongue projecting from the neck of the instrument into the body and terminating a short distance from the tail end and spaced 10 from the front and back thereof. A sound post extends from the top of the tongue to the front of the body. An auxiliary sound post extends from the bottom of the tongue to the back of the body and is adjustable to 15 tension the parts to the requisite degree to obtain the desired tonal results.

The invention relates to the manner of connecting the resilient tongue to the stem, and the formation of the auxiliary sound post 20 and the manner of connection between it and the back of the instrument.

While the drawing illustrates a preferred embodiment of the invention, it is to be understood that in adapting the means to meet 25 specific needs and requirements the design may be varied, and such other changes in the minor details of construction may be resorted to within the scope of the invention as claimed, without departing from the spirit 30 thereof.

For a full understanding of the invention and the merits thereof, reference is to be had to the following description and the drawing hereto attached, in which,—

35 Figure 1 is a central, longitudinal sectional view of the body portion of a stringed musical instrument embodying the invention.

Figure 2 is a vertical, transverse sectional view on the line 2—2 of Figure 1.

40 Figure 3 is an enlarged detail perspective view of the butt portion of the neck and the adjacent end of the resilient tongue, the parts being separated.

Figure 4 is an enlarged sectional view on 45 the line 4—4 of Figure 2.

Corresponding and like parts are referred to in the following description and designated in the several views of the drawing by like reference characters.

50 The body of the instrument comprises a

front 1, a back 2, and an outer connecting wall 3. The numeral 4 denotes the usual neck projecting from the body and receiving the finger board 5. The musical strings are designated by the numeral 6 and pass over 55 the usual bridge 7, and are connected at their rear ends to the tail piece 8. These parts are of well known construction and arrangement in a musical instrument of the violin type.

In accordance with the present invention the resilient tongue 9 is disposed within the body of the instrument and is spaced from the front and back thereof. The tongue 9 is thin and broad and terminates a short distance from the tail of the instrument, as indicated most clearly in Figure 1 of the drawings. The resilient tongue 9 may consist of metal or wood and is detachably connected to the butt of the neck 4. The end of the tongue 70 9 adapted to be coupled to the neck 4 is thickened and formed with a rib 10 which is adapted to obtain a snug fit within a groove 11 formed in the butt of the neck 4.

The rib and groove are of wedge shaped 75 outline to provide a dove tail joint which is made secure by glue or other determinate means.

A sectional sound post is disposed between 80 the tongue 9 and the front and back of the instrument. The top section of the post is designated by the numeral 11 and the bottom section by the numerals 12 and 13. The lower end of the section 11 is widened, as indicated at 14, and is tapered to a knife edge which 85 engages the top side of the tongue 9. The upper end of the section 11 is formed similar to the usual sound post. The members 12 and 13 comprising the bottom section of the sound post are connected by means of a screw thread 90 which provides for adjustment of the sound post to meet requirements. The part 13 has an opening formed therein which is threaded to receive the threaded stem of the part 12.

An outer flange 16 formed with the part 13 95 is confined between plates 15 bolted to the back 2 of the instrument. A portion is cut from the back 2 to receive the flange 16. The plates 15 and flange 16 result in a swivel connection of the part 13 with the back 2. The 100

upper end of the part 12 is widened, as indicated at 17, and terminates in a knife edge which engages the bottom side of the tongue 9.

5. Rotation of the part 13 effects a longitudinal movement of the part 12, with the result that the front and back of the instrument and the resilient tongue 9 are subjected to a variable tension which results in a modulation of the tone quality of the instrument. The sections comprising the sound posts are disposed out of line, as indicated most clearly in Figure 1 of the drawings. In the preferable arrangement the bottom section of the 10 sound post is set forwardly of the top section, and the latter is in line with the bridge 7 to sustain the direct stress of the musical strings 15 exerted upon the front 1. The invention may be applied to an instrument already completed by removing either the front or the back, the parts thus detached being subsequently replaced and glued to the part from which it was previously disengaged. The 20 resilient tongue 9 vibrates in unison with the front and the back of the instrument and adds to the tonal effect which is further varied by adjustment of the bottom section of the sound post to vary the tension upon the tongue and the front and back of the instrument.

30 Having thus described the invention, I claim:

1. The combination with the body of a 35 stringed musical instrument, and a resilient tongue therein connected at one end with the body of a sectional sound post having the sections interposed between and contacting with the tongue and front and back of the body, one of the sections comprising elements, one of which is connected to the back of the body 40 by means of a swivel joint, and the other element having an end portion in screw thread engagement with the element swiveled to the back of the body, and having its opposite end widened and terminating in a knife edge in 45 contact with the tongue.

2. A stringed musical instrument comprising a hollow body having a neck, a resilient tongue projecting into the body from the butt of the neck and terminating a distance 50 from the tail, and a sectional sound post having the sections interposed between and contacting with the said tongue and the front and back of the body.

3. A stringed musical instrument comprising a hollow body having a neck, a resilient tongue projecting into the body from the butt of the neck and terminating a distance 55 from the tail, and a sectional sound post having the sections interposed between and contacting with the said tongue and the front and back of the body, the bottom section being adjustable and positively connected to the back by means of a swivel joint.

4. A stringed musical instrument comprising a hollow body and neck, a resilient

70 tongue within the body and detachably connected to the butt of the neck, and a sectional sound post interposed between and contacting with the tongue and the front and the back of the body and having positive connection with the back by means of a swivel joint.

5. A stringed musical instrument comprising a hollow body having an opening in its back, a sectional sound post within the body, comprising two sections and means connecting them disposed between the front and the back thereof and including complementary elements having screw thread connection, one of the elements having an outer flange fitted in the opening provided in the back of the 75 body, and plates secured to opposite sides of the back and confining the said flange therebetween.

80 In testimony whereof I affix my signature.
